CLAIM

The ornamental design for portable warming apparatus, as shown and described.

DESCRIPTION

FIG. 1 is a perspective view of the top, front, and right side of the portable warming apparatus;

FIG. 2 is a perspective view of the bottom, front, and left side of the portable warming apparatus;

FIG. 3 is a perspective view of the bottom, rear, and right side of the portable warming apparatus;

FIG. 4 is a top view of the portable warming apparatus;

FIG. 5 is a bottom view of the portable warming apparatus;

FIG. 6 is a front view of the portable warming apparatus;
FIG. 7 is a right side view of the portable warming apparatus;

FIG. 8 is a rear front view of the portable warming apparatus; and,

FIG. 9 is a left side view of the portable warming apparatus. The text “45° C.” and the +, -, power, and clock symbols on the top of the portable warming apparatus form no part of the claimed design.

1 Claim, 9 Drawing Sheets
